CLAIM

The ornamental design for a lantern stove attachment, as shown and described.

DESCRIPTION

FIG. 1 is a top plan view of the lantern stove attachment showing my new design;

FIG. 2 is a front elevational view, the rear elevational view being substantially the same as shown;

FIG. 3 is a right side elevational view, the left side elevational view being substantially the same as shown;

FIG. 4 is a perspective view thereof; and

FIG. 5 is a bottom plan view thereof.

*Fig. 1**Fig. 2**Fig. 3*
